UNITED STATES PATENT OFFICE.

FRANK W. DAEMICKE, OF CHICAGO, ILLINOIS, ASSIGNOR TO PAUL J. DAEMICKE COMPANY, OF CHICAGO, ILLINOIS, A CORPORATION OF DELAWARE.

DISPLAY COUNTER.

Application filed April 11, 1927. Serial No. 182,738.

My invention relates to a refrigerated service display counter for perishable articles of food such as meat and the like; the invention having for its object the provision 5 of a construction whereby increased efficiency and economical refrigeration are obtained while at the same time a more sanitary display case or counter is provided whereby the food stuffs or meats are maintained at the proper temperature or in the desired chilled condition. Furthermore, with my improved construction the chilled condition in the food-stuff or meat holding portion, namely the bottom of the counter, 10 will be retained for a considerable period of time after the refrigerating unit has been shut down.

The above enumerated objects and advantages, as well as other advantages inherent 20 in my invention, will all be readily comprehended from the detailed description of the accompanying drawings, wherein—

Figure 1 is a perspective view of the rear side of my improved display counter with 25 the lower supporting portion broken away.

Figure 2 is a sectional view taken substantially on the line 2—2 of Figure 1 looking in the direction of the arrows.

Figure 3 is a horizontal sectional view 30 taken substantially on the line 3—3 of Figure 2 looking in the direction of the arrows.

Figure 4 is a detail sectional view taken on the line 4—4 of Figure 2 looking in the direction of the arrows.

Figure 5 is a transverse sectional view of 35 a portion of a display counter showing a modified form.

My invention relates to a refrigerated service display counter more especially intended 40 for containing and displaying meats and other food stuffs requiring a low temperature while on display. The specific type of display counter embodying my invention illustrated in the drawings involves 45 a suitable supporting frame or lower portion 10, while the upper portion constitutes the display counter proper. The forward side of the display counter usually consists of glass as at 11, held in place by suitable frames and at bottom by a sheet metal sealing strip 12, see Figure 2; while the rear or 50 salesman's side involves suitable slide doors

as at 13; the front and rear sides being preferably arranged at suitable and different inclinations so as to permit proper visibility 55 of the contents of the counter. The rear or salesman-side of the counter, at a suitable intermediate point, is provided with an inset ledge or scale holding portion as at 14.

Display counters of this general character are usually provided along the bottom and within the display portion with refrigerating coils as at 15 arranged in a horizontal plane lengthwise from end to end intermediate of the front and rear sides of the display counter, as more clearly shown in Figure 3, having the ingoing pipe 16 and the outlet pipe 17 which lead to a mechanical refrigerating unit located at a suitable place. My improved display counter also involves the 70 chilling coils 18 connected with the horizontally disposed pipe 19, a section whereof is connected with the inlet pipe 16. The coils are arranged in well known manner to induce proper circulation; the exposed portions of the coils inducing or exciting air circulation in the counter.

The chilling coils 15 have heretofore been arranged along the bottom of the counter with the bottom of the counter usually provided with a suitable perforated metallic plate arranged above the coils to provide an inner meat or food-stuff holding bottom.

My invention contemplates providing the bottom of the display counter with a suitable 85 wall of insulation as at 20, any suitable insulating material, such as cork or the like being employed. The cooling coils 15 are arranged a suitable distance above the main bottom of the display counter in order that 90 a considerable thickness of insulation may be employed as shown in Figure 2. The insulation 20, which is usually of cork, is formed about the lower sides and ends of the coils so as to provide a well or depression of 95 depth substantially equal to the diameter of the coils. The depression or channel is then provided with a layer 21, of waterproof and cold resisting material which is poured into the depression so as to fill the 100 channel and practically embed the chilling coils with the exception of the immediate upper surfaces thereof. The layer 21 is then covered with a layer 22 of hydraulically

setting cementitious material. This layer is of a suitable thickness to completely cover the tops of the coils 15 and preferably also to extend across the top of the insulating material 20; the cementitious material being molded or formed to provide the shoulder or flange portion 23 along the forward side of the case and the upstanding lip or flange portion 24 along the rear side of the case 10 in order to prevent moisture or water, during cleaning operation, from passing intermediate of the top layer and the frame and the cork or insulation of the case.

In Figure 5 I show a modification of the invention. The display counter of Figure 5 in general construction may be like that previously described, having the main bottom 25 provided with a suitable layer of insulating material 20 of cork and the like 20 as in the construction described; with the cooling coils 15 in the well or depression formed in the upper surface. The coils 15 are preferably entirely embedded, except for the tops thereof, in a plastic water-proof, 25 cold resisting material 21. The tops of the coils are then preferably covered with the layer of cementitious material 22 like in the previously described construction; and before this layer 22 has become set, I place 30 a plate of metal 26 thereon, namely a metal which will readily transfer the cold, such as porcelain enameled iron; the plate being pressed into the cement so as not to leave an air space therebeneath. It is apparent 35 that a bottom which is impervious to moisture is thus provided and a sanitary counter produced while at the same time a good cold conducting bottom for conveying the chilling effect of the coils to the material placed 40 on the bottom of the counter is obtained.

With these constructions it is apparent that the coils are fully covered or encased and that with the insulating material 20 therebeneath and the cold resisting plastic material around the sides of the coils, the pipes or coils 15 are sealed against air, the cold temperature or condition of the coils conserved and the cold practically entirely transmitted to the outer or top covering 22 of 45 cementitious material, or to the metal plate 26 when the latter is employed.

The plate 26, like the cementitious material or covering 22, is preferably formed along the edges with the upwardly disposed flanges or raised portions 27, 28 which may extend slightly beyond the insulation and the coil embedding material to prevent water or moisture finding its way to the insulating material therebeneath. As a result 55 a more sanitary display counter is provided than has heretofore been the case; while at the same time a counter which can be readily cleaned is produced.

The coils, as can be seen in the drawings, 60 are encased in a jacket, the lower part

whereof consists of the insulating material 20 and the water-proof, cold resisting material 21, while the upper part consists of the hydraulically setting cementitious material 22 with or without the comparatively 70 heavy metal plate 26; the upper part of the jacket being a ready conductor or transmitter of the cold temperature of the coils, while at the same time retaining its chilled condition for a comparatively long period 75 after the refrigerating unit has been shut down. As a result, a considerable saving in operating expense is effected because of the retentive quality of the upper covering, while at the same time a more effective and 80 uniform chilling of the meats and other food-stuffs is obtained because the latter may be placed directly on the chilled upper portion of the jacket.

In order to prevent accumulation of moisture and also permit proper drain of water while the counter is being washed or cleaned, suitable drain-pipes 29 are provided, leading from suitable points adjacent to the forward side and opposite ends of the 90 counter; it being usual in counters of this character to have the bottom of the counter slope slightly downward toward the front in order to increase visibility of all the articles on display. The drains 29 may have 95 suitable closures or water-seals to prevent ingress of air and insects.

It is understood, of course, that counters of the character in question are not intended for use as refrigerators but merely as display cases for certain food-stuffs or meats, and therefore it is merely essential to maintain a proper low temperature at the bottom of the counter where the food-stuffs or meats are arranged in visible order. 105

In forming the rear wall of the counter at an intermediate point with a weighing scale holding chamber 14, opportunity for arranging the upper coils 18 is afforded at a place where they will not interfere with 110 the salesman's vision of the counter contents and his accessibility to the counter. At the same time the scale will be conveniently located adjacent to the slides or doors 13 so that weighing of various cuts of meats or 115 other food-stuffs, before final selection, may be made and the unselected material replaced in the counter, without material loss in its chilled condition.

The invention, as exemplified in the drawings, has been described in terms employed merely for description and not as terms of limitation. 120

What I claim is:

A display counter of the character described having glass side walls, the bottom being provided with insulating material formed to provide a recess on its upper surface extending substantially from front to rear and from end to end, refrigerating coils 125 130

arranged in the recess, an enclosure for said coils consisting of plastic water and cold resisting material filling said recess and embedding the coils except for the top surfaces thereof, a covering of cold conducting and temperature retaining cementitious material arranged in intimate contact with said plastic material and the tops of the coils so as to prevent passage of air and moisture therebeneath, and drain outlets extending 10 downwardly from said covering to the bottom of the counter.

FRANK W. DAEMICKE.
